(57) **CLAIM**

The ornamental design for a six-sided die, as substantially shown and described.

DESCRIPTION

FIG. 1 is an isometric view showing the front, top and left side of a six-sided die design;

FIG. 2 is an isometric view showing the bottom, back and right side of the six-sided die design, which is an opposite and flipped perspective of that shown in FIG. 1;

FIG. 3 is a top view of the die shown in FIGS. 1 and 2, wherein the visible side includes six grooves;

FIG. 4 is a front view of the die shown in FIGS. 1 and 2, wherein the visible side includes five grooves;

FIG. 5 is a bottom view of the die shown in FIGS. 1 and 2, wherein the visible side includes four grooves;

FIG. 6 is a rear view of the die shown in FIGS. 1 and 2, wherein the visible side includes three grooves;

FIG. 7 is a right side view of the die shown in FIGS. 1 and 2, wherein the visible side includes two grooves; and

FIG. 8 is a left side view of the die shown in FIGS. 1 and 2, wherein the visible side includes a single groove.

FIG. 9 is an isometric view showing the front, top and right side of the six-sided die design;

FIG. 10 is an isometric view showing the front, bottom and right side of the six-sided die design;

FIG. 11 is an isometric view showing the front, bottom and left side of the six-sided die design; and,

FIG. 12 is an isometric view showing the back, bottom and left side of the six-sided die design.
